(57) **CLAIM**

The ornamental design for a lamp as shown and described.

DESCRIPTION

FIG. 1 is a front-right top perspective view of a lamp according to a first embodiment of the present invention;

FIG. 2 is a front-right bottom perspective view of the lamp thereof;

FIG. 3 is a rear-right top perspective view of the lamp thereof;

FIG. 4 is a rear-left bottom perspective view of the lamp thereof;

FIG. 5 is a front plan view of the lamp thereof;

FIG. 6 is a left-side plan view of the lamp thereof;

FIG. 7 is a rear plan view of the lamp thereof;

FIG. 8 is a top plan view of the lamp thereof;

FIG. 9 is a bottom plan view of the lamp thereof;

FIG. 10 is a front-right top perspective view of a lamp according to a second embodiment of the present invention;

FIG. 11 is a front-right bottom perspective view of the lamp thereof;

FIG. 12 is a rear-right top perspective view of the lamp thereof;

FIG. 13 is a rear-left bottom perspective view of the lamp thereof;

FIG. 14 is a front plan view of the lamp thereof;

FIG. 15 is a left-side plan view of the lamp thereof;

FIG. 16 is a rear plan view of the lamp thereof;

FIG. 17 is a top plan view of the lamp thereof;

FIG. 18 is a bottom plan view of the lamp thereof;

FIG. 19 is a front-right top perspective view of a lamp according to a third embodiment of the present invention;

FIG. 20 is a front-left bottom perspective view of the lamp thereof;

FIG. 21 is a rear-left top perspective view of the lamp thereof;

FIG. 22 is a rear-left bottom perspective view of the lamp thereof;

FIG. 23 is a front plan view of the lamp thereof;

FIG. 24 is a right-side plan view of the lamp thereof;

FIG. 25 is a rear plan view of the lamp thereof;

FIG. 26 is a top plan view of the lamp thereof;

FIG. 27 is a bottom plan view of the lamp thereof;

FIG. 28 is a front-right top perspective view of a lamp according to a fourth embodiment of the present invention;

FIG. 29 is a front-left bottom perspective view of the lamp thereof;

FIG. 30 is a rear-left top perspective view of the lamp thereof;

(Continued)

FIG. 31 is a rear-left bottom perspective view of the lamp thereof;

(56)

FIG. 32 is a front plan view of the lamp thereof;

FIG. 33 is a right-side plan view of the lamp thereof;

FIG. 34 is a rear plan view of the lamp thereof;

FIG. 35 is a top plan view of the lamp thereof; and,

FIG. 36 is a bottom plan view of the lamp thereof.

The dashed lines of FIGS. 3, 4, 7, 9, 10-16, 18, 21, 22, 25, 27-34, and 36 formed by equal dash broken lines represent portions of the article and form no part of the claimed design. The dashed lines of FIGS. 10-15, and 28-33 formed by the dash-dot-dash broken lines represent boundaries and form no part of the claimed design.

Although not shown, the left-side view of the first and second embodiments are mirrored image of the right-side view of those respective embodiments.

Although not shown, the right-side view of the third and fourth embodiments are mirrored image of the left-side view of those respective embodiments.

1 Claim, 36 Drawing Sheets
